UNITED STATES PATENT OFFICE.

WILLIAM H. BRISTOL, OF HOBOKEN, NEW JERSEY.

DESIGN FOR A CASE FOR RECORDING-GAGES.

SPECIFICATION forming part of Design No. 30,194, dated February 14, 1899.

Application filed November 11, 1898. Serial No. 696,184. Term of patent 14 years.

To all whom it may concern:

Be it known that I, WILLIAM H. BRISTOL, a citizen of the United States of America, residing at Hoboken, in the county of Hudson and State of New Jersey, have invented and produced a new and original Design for Cases for Recording-Gages, of which the following is a specification, reference being had to the accompanying drawings, in which—

10 Figure 1 represents a front elevation of a case for a recording-gage embodying my new design. Fig. 2 is a perspective view of the same.

15 As shown in the drawings, the leading features of my design consist in a front C, having its outer periphery a concentric with the outer periphery of the body of the case B and

its inner periphery b eccentric with said outer periphery a, thus forming an eccentric opening through which the chart D is seen concentric with said inner periphery.

Having thus described my invention, what I claim as new, and desire to secure by Letters Patent, is—

The design for a case for recording instruments, as herein shown and described.

In testimony whereof I have hereunto set my hand in the presence of two subscribing witnesses.

WILLIAM H. BRISTOL.

Witnesses:

EUGENIE P. HENDRICKSON,
ALFRED J. EISENTRAUN.
